UNITED STATES PATENT OFFICE

CHARLES J. NASH, OF CHICAGO, ILLINOIS, ASSIGNOR TO UNIVERSAL DRAFT GEAR ATTACHMENT CO., A CORPORATION OF ILLINOIS

SLACK ADJUSTER FOR RAILWAY CAR BRAKES

Application filed November 14, 1928, Serial No. 319,254. Renewed August 11, 1930.

The invention relates to manually operated adjusters for the foundation brake rigging of a railway car, its objects being to secure simplicity and reliability of action, with adequate strength to withstand the stresses of service.

A preferred embodiment of the invention is hereinafter described and is illustrated in the accompanying drawings, in which

Fig. 1 is a detail, diagrammatic view of the foundation brake rigging as applied to a railway car;

Figs. 2, 3, 4 and 5 are views in perspective of various elements of the adjusting mechanism;

Fig. 6 is a detail plan view of the regulator, the parts being in the position they occupy upon installation;

Fig. 7 is a detail, vertical, longitudinal, section of the adjusting mechanism taken on the line 7—7 of Fig. 6, the parts being in the same position as in Fig. 6;

Fig. 8 is a similar view, the parts being shown in a position assumed during the adjusting operation; and

Fig. 9 is a detail section on the line 9—9 of Fig. 6.

A pair of car sills is represented at 10; a pair of car wheels with their associated brakes is shown at 11, 11, one pair for each truck; the usual brake cylinder is represented at 12 and its piston rod at 13, the latter being attached to a live lever 14. A pull rod 15 connects the opposite end of the lever 14 with a brake lever of one of the trucks. A pull rod 16 connects the lever 14, intermediate of its ends, with a dead cylinder lever 17 which in turn is connected by a pull rod 18 with one of the brake levers of the other truck.

The lever 17 is pivoted to an adjustable block 19 which is slidably mounted upon a bar 20 rigidly attached to the car frame, as to one of the sills 10, by means of brackets 21, 22. The body of the block 19 is enclosed within a box-like rider 23, the ends of which are apertured, as indicated at 24, 25, to receive the bar 20 upon which it is slidably mounted.

The parts 19 and 23 are so proportioned that they are capable of relative movement corresponding with the normal slack of a

newly installed brake mechanism. A pawl element 26 in the form of a bar having ratchet teeth 27 on its lower face is mounted above the rider 23 and cooperates with ratchet teeth 28 formed on the upper face thereof. This pawl element is pivotally attached to a block 29 sleeved upon and permanently secured to the bar 20 as by means of a bolt 30. Preferably the pawl element 26 is readily detachable from its pivot and for this purpose, its pivot bearing takes the form of a hook 31 which engages under the pivot 32.

Brake application force tends to move the pivoted end of the lever 17 to the left, having reference to Fig. 1, and consequently it may be said that the forward end of the adjusting mechanism is at the left. The ratchet teeth 27 face backwardly while the teeth 28 face forwardly. Normally the block 19 is at the forward end of the rider 23 and the force incident to brake application is, therefore, transmitted through the block 19, the forward end of the rider 23, the ratchet teeth 28, 27, the pawl element 26 and the pivot block 29 to the bar 20.

The pawl element 26 is longitudinally and vertically slotted as shown at 33 to receive a post 34 rising from the rider 23, and a pin 35 set through the post above the pawl prevents the teeth of the latter from being jarred out of engagement from the teeth of the rider. The rear end of the pawl element 26 is shaped to form a convenient handle 36 by means of which it may be swung upwardly upon the removal of the pin 35.

An upstanding loop 37 ties the two side members of the pawl element together and insures adequate strength. A handle 38 may depend from the pivot block 19 for convenience in manually shifting the same upon the bar 20.

Upon the installation of a new set of brake shoes, the lever 17 and the parts of the slack adjusting mechanism are positioned as shown in Figs. 6 and 7, and continue to occupy these positions in service except that as the brake slack is increased, as by the wearing away of the faces of the shoes, the recession of the brakes may shift the pivot block 19 backwardly. The travel of the cylinder piston in

applying the brakes will be increased to the extent of this increase of slack. This increase of travel being undesirable, the abnormal slack is taken up by first removing the pin 35, then raising the pawl element 26 to disengage the ratchet teeth, drawing back the pivot block 19, thereby advancing the brake shoes. This backward movement of the pivot block within the limits of the rider 23 corresponds with the normal brake slack but is continued until the brakes are brought firmly against the wheels, the rider 23 being moved backwardly to a corresponding extent. Thereupon the pawl element is lowered to bring the ratchet teeth again into engagement, the rider being held in its new retracted position.

The pin 35 being re-inserted, the adjusting operation is completed and the brake system will operate with the desired range of piston travel.

Upon release of the pivot block 19, its forward movement is arrested when it reaches the end of the rider and in subsequent brake applications, the shoes are set firmly against the wheels by the normal piston travel.

I claim as my invention:

1. In a brake adjusting mechanism, in combination, a fixed bar, a pivot block for the attachment of a brake lever and slidably mounted on the bar, a box-like rider slidably sleeved upon the bar and enclosing the block, such block and rider having relative movement corresponding to the normal slack in the brake system, a bar anchored against longitudinal movement, and means for interlocking the last named bar to the rider in different positions of the latter.

2. In a brake adjusting mechanism, in combination, a fixed bar, a pivot block for a brake lever slidable on the bar, a rider slidably mounted on the bar and having abutments for engaging both ends of the block and spaced to permit relative movement of the block and rider corresponding with the normal slack of the brake system to be regulated, a bar fixed against longitudinal movement and interlocking with the rider in any of the positions it may occupy on the bar.

3. In a brake adjusting mechanism, in combination, a fixed bar, a pivot block for a brake lever loosely sleeved upon the bar, a rider loosely sleeved upon the bar, and having abutments engageable with both ends of the block and spaced to permit limited relative movement of such two elements, and a ratchet bar anchored against longitudinal movement and engageable with ratchet teeth on the rider in a plurality of positions of the rider on the fixed bar.

4. In a brake adjusting mechanism, in combination, a fixed bar, a pivot block for a brake lever loosely sleeved upon the bar, a rider loosely sleeved upon the bar, and having abutments engageable with both ends

of the block and spaced to permit limited relative movement of such two elements, a ratchet bar anchored against longitudinal movement and engageable with ratchet teeth on the rider in a plurality of positions of the rider on the fixed bar, and means for locking the ratchet bar in engagement with the rider. 70

5. In a brake adjusting mechanism, in combination, a fixed bar, a fulcrum element supported by the bar and adjustable longitudinally relatively thereto, an adjustable abutment element engageable by the fulcrum element in both directions of movement thereof, and locking means fast on the bar and having a plurality of engaging devices to hold the abutment element in a corresponding number of adjusted positions. 75

6. In a brake adjusting mechanism, the combination of a fixed bar, a pivot block for a brake lever slideable on the bar, a rider slidably mounted on the bar having abutments for engaging both ends of the block and spaced to permit relative movement of the block and rider corresponding with the normal slack of the brake system to be regulated, a rack tooth on the rider, and a pivoted rack bar attached to the fixed bar cooperating with the tooth on the rider to regulate the mechanism when excess slack exists. 85 90

7. In a brake adjusting mechanism in combination, a flat bar fixed to the car, a block sleeved on the bar and adapted to pivotally support the fulcrum of a brake lever, a rider adjustably mounted on the bar to regulate the mechanism, a tooth on the rider and a pivoted rack bar secured to the fixed bar and cooperating with the rider tooth to hold the rider fixed against movement by brake application stresses. 100 105

8. In a brake adjusting mechanism, the combination of a fixed bar, a block slideable on the bar and adapted to pivotally support the fulcrum of a brake lever, a rider supported by the bar and limiting free movement of the block to normal brake shoe clearance, and means including a swinging rack bar for positioning the rider relative to the fixed bar for adjusting the mechanism. 110

9. In a brake adjusting mechanism, the combination of a fixed bar, a block slideable on the bar and adapted to pivotally support the fulcrum of a brake lever, a rider supported by the bar and limiting free movement of the block to normal brake shoe clearance, means including a swinging rack bar for positioning the rider relative to the fixed bar for adjusting the mechanism, and means for locking the rack bar to hold the adjustment. 115 120 125

In testimony whereof I affix my signature.
CHARLES J. NASH.
